(57) **CLAIM**

The ornamental design for an combination adapter and data transmission cable, as shown and described.

DESCRIPTION

FIG. 1 is a top view of a combination adapter and data transmission cable, showing my new design;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a perspective thereof; and,

FIG. 8 is a perspective view thereof in a folded position. The design is an adapter/data transmission cable comprising two connecting ends.

The wire frame lines shown in the perspective views are intended to indicate surface contour.

1 Claim, 6 Drawing Sheets
